UNITED STATES PATENT OFFICE.

CHARLES H. BACH, OF LACONIA, NEW HAMPSHIRE.

PUMP.

1,388,087.

Specification of Letters Patent. Patented Aug. 16, 1921.

Application filed January 9, 1920. Serial No. 350,256.

To all whom it may concern:

Be it known that I, CHARLES H. BACH, a citizen of the United States, residing at Laconia, in the county of Belknap and State 5 of New Hampshire, have invented new and useful Improvements in Pumps, of which the following is a specification.

This invention relates to pumps and the principal object of the invention is to provide means for furnishing a large supply 10 of water such as for irrigation purposes and the like.

Another object of the invention is to make the device out of tubing with the various 15 cylinders and pipes connected together to form a supporting frame with the ends of the outlet pipe extended and provided with foot portions on which the frame rests.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

Figure 1 is an elevation of one form of the invention with parts shown in section.

Fig. 2 is a view taken at right angles from Fig. 1.

Fig. 3 is an elevation showing a pump provided with a pair of cylinders and outlet pipes.

Fig. 4 is a horizontal section showing a pump provided with four outlet pipes.

Referring to the Figs. 1 and 2, A indicates the frame which is formed of the discharge pipes 1 and 2, the cylinder 3 and its suction chamber 4 and the cross pipes 5 and 5', the pipes being connected together 40 by the couplings 6 and 6'. As will be seen the cylinder is located between the discharge pipes with its chamber 4 located above the plane of the lower ends of said discharge pipes. These lower ends are screw threaded 45 and receive screw threaded foot portions 7 which form rests for the frame. In this way the chamber 4 is supported above the bottom of the well.

The suction chamber 4 has a valve seat 8 55 formed in its lower end and this end is closed by a screen 9. This screen is held

in place by the bolts 10 and these bolts also connect the upper end of the chamber with the lower end of the cylinder 3. Openings are formed in the sides of this chamber and 60 these openings receive the cross pipes 5. A valve 11 is arranged in the chamber and the valve rod 12 has its ends carried by spiders 13 at the upper and lower ends of the chamber. A spring 14 on said rod tends to hold 65 the valve upon its seat.

A piston 15 is located in the cylinder 3 and the piston rod 16 passes through the coupling 6' which is connected with the upper end of the cylinder and through a 70 sleeve 17 carried by the upper cross pipe 5'. The upper end of the piston rod is provided with openings 18 by which it may be bolted to the reciprocating rod of a windmill or the like, though I prefer to operate the pump 75 from a crank shaft, suitably driven, as will be described hereinafter.

The piston rod passes through a packing gland 19 formed in the central coupling 6', connected to the top of the cylinder 3, and 80 this gland is formed of a pair of plates 20, suitably supported in the coupling and clamping between them a pair of rings 21 formed of leather or the like. These rings have their inner edges folded over the inner 85 edges of the plates and encircle the piston rod.

The coupling 6 which connects each of the discharge pipes with its pipe 5 is provided with a valve seat 23 which is located 90 above the point of junction of said pipe 5 with the coupling. A valve 24 slidably mounted on the stem 25 is normally held on this seat by the spring 26. The stem is carried by the spiders 27 at the ends of the 95 coupling.

These discharge pipes extend upwardly through the frame and have their upper ends suitably formed to receive connections for carrying the water to the desired point. 100 They are provided with the small holes 28 by which the water may leak from the pipes so as to prevent freezing in cold weather.

A platform 29 is supported by the frame at one side thereof and this platform carries the uprights 30 in which the crank shaft 31 is journaled. This crank shaft is provided with the hand wheel 32 and the pulley 33 so that the shaft may be driven manually or by motive power. A pitman 34 connects the shaft with the piston rod and this pitman is connected with the shaft by the 110

flexible connection 35. It is connected with the piston rod by the flexible joint 36.

It will thus be seen that when the piston is reciprocated in its cylinder by means of the rotation of the crank shaft or by means of a windmill or the like, the upward stroke of the piston will create a suction in the chamber and this suction will raise the valve and draw water from the well into the chamber. This upward stroke of the piston will also hold the valves 24 of the discharge pipes upon their seats. On the downward stroke the valve 11 in the suction chamber will close and the water in said chamber will be forced by the piston through the pipes 5 into the discharge pipes and the pressure will raise the valves 24 to permit the water to pass into the upper parts of said discharge pipes. On the next upward stroke of the piston these valves 24 will close to prevent the water in the discharge pipes from flowing back into the suction chamber and a new charge of water will be sucked into said chamber from the well.

In the form shown in Fig. 3 I provide a pair of pumps, each pump being indicated by the character B and each pump is connected with a discharge pipe C. The piston rods of these pumps are connected with the crank shaft 31' which is provided with two cranks, as shown, said cranks being arranged to give one piston its down stroke while the other piston is on its up stroke. Each of the pumps and each of the discharge pipes is provided with a wide base part 7 for supporting the apparatus and the base parts of the pumps are connected with the lower ends of the suction chambers by the tubular members 7* which are provided with the slots 7". These parts are connected together by suitable bolts, as shown.

When this apparatus is placed in the well or irrigation ditch the water will flow through the slots 7" into the tubular members and from said members will pass into the suction chambers.

In other respects this form of the invention is similar to that before described.

I may form the pump of large dimensions and connect it with a plurality of outlet pipes as shown in Fig. 4. This figure shows the pump D connected with the four outlet pipes E by the connections F.

It will thus be seen that I have produced an apparatus which is of simple construction and one which will provide a large flow of water for irrigation purposes and the like. The entire apparatus may be placed in the pond or ditch containing the water and the

discharge pipes provided with connections 60 for leading the water a great distance from the apparatus.

It is thought from the foregoing description that the advantages and novel features 65 of my invention will be readily apparent.

I desire it to be understood that I may make changes in the construction and in the combination and arrangement of the several parts, provided that such changes fall within the scope of the appended claims.

What I claim is:—

1. An apparatus of the class described comprising a frame formed of tubing and including a suction chamber having an inlet opening in its bottom, a spring 75 pressed valve controlling said opening, a cylinder having its lower end in communication with the suction chamber, a piston in said cylinder, a piston rod connected with the piston and passing through the upper 80 end of the cylinder, vertically arranged discharge pipes arranged parallel with the cylinder and suction chamber, transverse tubing connecting the discharge pipes with the cylinder and chamber and the tubing connected with the chamber being in communication with said chamber and said discharge pipes, spring controlled valves in said discharge pipes, a platform supported on the frame, uprights supported on the platform, 90 a crank shaft carried by said uprights and a pitman connecting the crank shaft with the piston rod.

2. An apparatus of the class described comprising a frame formed of tubing and 95 including a cylinder, a piston therein, a piston rod connected with the piston and passing through the upper end of the cylinder, a suction chamber connected with the lower end of the cylinder and having an inlet opening in its bottom, a spring valve controlling said opening, a supporting member connected with the lower end of the suction chamber and having slots therein for permitting the passage of water to the inlet 100 opening, a vertically arranged discharge pipe, transverse tubing connecting said discharge pipe with the cylinder and chamber, the tubing connected with the chamber being in communication with such chamber and the discharge pipe, a spring controlled valve in said discharge pipe, a platform supported on the frame, uprights on the frame, a crank shaft carried by the uprights and a pitman connecting the said shaft with the piston 110 rod.

In testimony whereof I affix my signature.
CHARLES H. BACH.
